UNITED STATES PATENT OFFICE.

JOHN H. BEST, JR., OF SANDUSKY, OHIO.

TROLLEY-PROTECTOR.

SPECIFICATION forming part of Letters Patent No. 761,574, dated May 31, 1904.

Application filed January 8, 1904. Serial No. 188,163. (No model.)

To all whom it may concern:

Be it known that I, JOHN H. BEST, Jr., residing in Sandusky, in the county of Erie and State of Ohio, have invented a new and Improved Trolley-Protector, of which the following is a specification.

This invention relates to trolleys for electric motors.

The invention consists of novel and improved means serving to prevent jumping action of the trolley from the conductor-wire, which means has the further advantage in being constructed adapted for allowing free passage of the trolley along the conductor-wire without liability to damage from engagement with projections thereon—such as switches, hangers, and other devices—likely to engage with trolley-protectors as they have been heretofore constructed, all as will hereinafter be fully described, and the novel features pointed out in the claims.

Reference is had to the accompanying drawings, in which—

Figure 1 is a side elevation illustrating my invention in use. Fig. 2 is an elevated rear view; Fig. 3, a detail broken-away sectional view taken on line 3 3 of Fig. 1, and Fig. 4 is a detail sectional view taken on line 4 4 of Fig. 1.

In carrying out my invention I employ any suitable form of trolley-head A, having forks B, providing support for the usual sheave C on an axle, which may be in the nature of a simple bolt D, having support at the upper end of the forks, as best shown in Fig. 3.

At opposite sides of the sheave C, I fixedly arrange plates E, having support on the axle D by approved means, serving to prevent rotation, and washers F, arranged between the plates E and the sheave C, may also be used.

At the upper end or top edge of the plates E, I provide yielding and abutting dogs G, having stems H, made projecting, adapted for connection to the upper ends of levers I, having fulcrums at J on the plates E and secured by suitable headed pins K. (See Fig. 4.) It will be noticed that the abutting ends of the dogs G are enlarged and made rounding or curved, whereby upon contact with a fixed object on the conductor-wire they will be separated against tension of the springs L on the

dog-stems H. The springs are arranged in suitable recesses L' in the inner sides of the plates E, with their ends confined between the enlarged head on the dogs and the bottom or inner wall of the recesses.

The lower ends of the levers I are connected by two ends M of a rope N, which latter extends down through an eye O.

My invention will be understood from the above description. The rope N is the common means employed for pulling down the trolley-pole. Now obviously when the rope N is pulled, as stated, the lower ends of the levers I will be drawn together through connection of the two ropes M, and thereby effect sufficient separation of the dogs G against tension of the springs L to permit passage between them of the conductor-wire. The main object of the dogs G is to prevent jumping of the trolley from the conductor-wire. Through their construction, however, they have additional advantage in being made yieldingly end-wise separable to permit free passage over obstructions on the conductor-wire.

Having thus described my invention, what I claim as new, and desire to secure by Letters Patent, is—

1. The combination in a trolley-protector, of rigid plates at opposite sides of the trolley-sheave, levers fulcrumed on the said plates, operating-ropes extending from the lower ends of the said levers, and yielding abutting dogs at the upper ends of the levers, the contacting faces of the dogs being adapted to be laterally separated upon contact with a projection on the conductor-wire.

2. The combination in a trolley-protector, of rigid plates at opposite sides of the trolley-sheave, levers fulcrumed on the said plates, operating-ropes extending from the lower ends of the said levers, laterally-yielding dogs at the upper ends of the levers, receding contacting faces on the said dogs, springs on reduced ends of the dogs, the springs being located in recesses in the said rigid plates and between the dog-heads and the plates, substantially as described.

JOHN H. BEST, JR.
